UNITED STATES PATENT OFFICE.

ERNST W. F. HERRMANN, OF SAN ANTONIO, TEXAS.

BIPLANE.

1,105,429.

Specification of Letters Patent. Patented July 28, 1914.

Application filed November 21, 1911. Serial No. 661,603.

To all whom it may concern:

Be it known that I, ERNST W. F. HERRMANN, a citizen of the United States, and a resident of San Antonio, in the county of 5 Bexar and State of Texas, have invented a new and Improved Biplane, of which the following is a full, clear, and exact description.

My invention relates to a new and improved form of biplane, and the principal object of my invention is to provide a flying machine of the above-indicated type, having a relatively high degree of stability and effective supporting surfaces proportionate to 10 the relative small area of the supporting planes.

A further object of my invention is to dispose a pair of propellers in such position as to give the greatest lifting effect to the 15 machine, and to so dispose the propellers as to obtain the greatest efficiency.

A further object of my invention is to provide a landing device adapted to absorb the shock to the machine in landing, and to 20 draw the same up close to the body of the machine while the same is in flight.

A further object of my invention is to provide a new and improved form of unitary steering mechanism by which the 25 machine may be guided in all magnitudes.

To these ends, the invention consists in the novel construction, combination, and arrangement of parts, as hereinafter described and claimed.

Reference is to be had to the accompanying drawings, forming a part of this specification, in which similar characters of reference indicate corresponding parts in all 35 figures, and in which—

Figure 1 is a plan view of a preferred embodiment of my invention, portions of the top planes of both the forward and the rear sets of planes being broken away to show the parts beneath; Fig. 2 is a side elevation of the same on a slightly reduced scale; Fig. 3 is a perspective view of the steering mechanism; Fig. 4 is a side elevation of the same; Fig. 5 is a front elevation with the front propeller and landing mechanism omitted; Fig. 6 is a plan view partly in section of a portion of the mechanism for operating the swinging ends of the lower forward plane; Fig. 7 is a side view of another portion of the same mechanism; Fig. 8 is a side elevation of the landing mecha-

nism; Fig. 9 is a plan view looking down upon the same, Fig. 10 is a detailed perspective view of a holding clamp on the landing mechanism.

Described more in detail, the biplane comprises a general framework 7, supporting a pair of forward planes 8 and 9, each of said planes being substantially rectangular in shape and of materially greater width than depth, the central rear portion of each plane being recessed, to form a central opening 10. The upper plane 9, as shown more clearly in Fig. 1, is of less width than the lower plane, and the side edges 11 of this upper plane converge slightly toward the rear, to 65 meet the rear side forming the curved outline of the upper recess. Each side edge of the lower forward plane has extensions 12 thereon of general triangular construction, which extensions are movable vertically to 70 coact with the rudder, to guide the biplane. The rear set of planes 13 are each in the general form of a trapezoid, with the smaller base forward. These rear planes are superimposed and have their central 75 forward portion recessed, as shown at 14 in Figs. 1 and 2, to form a general trapezoidal opening, forming a rearward extension of the central opening 10. The lower plane of the rear set of planes 13 is arranged as a lifting plane (front high, rear 80 low), and the upper plane of same is arranged as a non-lifting plane (set flat, level), both to coact with each other in combination to give out the greatest amount of 85 steadiness to the plane as a whole, and for keeping the aeroplane from falling into holes in the air. Rearwardly converging braces 15 from the rear planes 13, have positioned between them, a pair of spaced- 90 apart vertically-extending parallel, horizontal rudders 16, fastened to each other by a strut 17, attached to which strut is a pair of flexible wires 18 leading about pulleys 19 and 20 mounted on opposite sides of the machine between the forward planes, and about pulleys 21 disposed beneath the operator's seat 30, to the opposite ends of the transversely-disposed arms 22 mounted adjacent the lower end of a steering post 23 positioned in front of the operator's seat. The lower end of this steering post is connected to the supporting frame 7 by means of a ball-and-socket joint 24, the upper end of the steering post 23 having affixed thereto, 100

105

110

a conventional form of steering wheel 25. By this construction, the rotation of the wheel 25 to the right or left, will correspondingly change the angle of the rudders 16, to guide the machine horizontally.

The ends 12 of the lower forward plane 8 are hinged at 12^a to have vertical movement and when the said ends are swung up or down as hereinafter described the front edges of the plane will be raised and lowered as in my Patent No. 1,011,620 dated December 12, 1911.

The means for operating the ends 12 of the plane consists of a flexible connection 251 secured to and disposed about a pulley 26 and passed in opposite directions about a pair of pulleys 27, each mounted on a vertically-extending rod or shaft 27' on opposite sides of the post 23, said flexible connection 20 is then looped in opposite directions about one of a pair of semi-circular peripherally grooved members 28 rigidly mounted on the post 23, which members have their peripheries disposed on opposite sides of 25 the post above the arm 22, as shown more particularly in Figs. 3, 4 and 6. This construction is duplicated on opposite sides of the steering post 23, so as to facilitate the flexing of either side of the plane 30 simultaneously with the actuation of the pair of horizontally-steering rudders 16. The operation is as follows: In ascending the hand wheel 25 is swung rearwardly into the position shown in dotted lines in Fig. 6, 35 when the ends 12 of the plane will be swung up and the parts assume the position shown in Fig. 5. To descend the hand wheel 25 is swung forwardly into the position shown in full lines in Fig. 6 when the ends will be 40 lowered.

Disposed centrally between the planes 8 and 9, is a compound engine 29, preferably composed of two parts, each part disposed on opposite sides of the operator's seat 30, 45 convenient to the wheel 25, and adapted to operate the two independent propeller shafts through the medium of a dual drive mechanism 31, forming the subject-matter of my copending application, Serial No. 661,604, 50 filed November 21, 1911, said mechanism adapted to be coupled up at will to a rearwardly-facing propeller 32 mounted upon the framework supporting the lower forward plane, in elevation substantially half 55 way between the lower forward plane 8 and the upper forward plane 9, shown in Fig. 2, and in plan within the contour of the opening 10, as shown more particularly in Fig. 1. The forwardly-extending propeller 33 is 60 mounted on a shaft 34, which shaft is positioned above the lower plane 8, at a slight acute angle to the same, and extends some material distance forward of the front edge of the lower plane 8, as shown more particu- 65 larly in Fig. 2.

The rear end of the device is supported when on the ground, by means of a roller 35 mounted in a bracket 36, which bracket is in turn rotatably supported through the medium of a vertically-extending pin 37 carried on the lower bracketed end of a centrally-disposed, rearwardly-extending, vertical frame 38 suitably braced from the rear central portion of the framework 7. The bracket 38 is maintained in the central vertical plane of the machine, by means of a coil spring 39 encircling the pin 37 and having its opposite ends engaging the bracket and pin.

In order to support the front end of the machine and to form a combined landing device and shock absorber for the same, there extends forwardly of the machine, a pair of transversely-disposed spaced-apart wheels 85 parallel to each other, each of which wheels 80 is journaled in a forked bar 41, said bar being fulcrumed on pins 42 to a downwardly- and forwardly-extending member 43 forming part of the framework 7, and normally supported on the same, to form an extension 90 thereto. The members 43 are connected by means of a transversely-disposed brace bar 44, forming part of the framework 7, which brace bar may carry the steering mechanism hereinbefore described and shown in detail 95 in Fig. 3. The forked bar 41 has an aperture 45 extending vertically therethrough, within which aperture is positioned an upwardly and rearwardly-extending arched rod 46 rigidly mounted upon the lower end of each member 43, the said lower end extending a distance below the pivot 42. The upper end of the rod 46 terminates in a cap 47, bearing upon which cap is one end of a coil 100 spring 48, encircling the rod 46, the opposite lower end of which spring is adapted to bear upon a removable catch plate or stop 49 105 slidably mounted upon the top of the forked bar 41, as shown more particularly in Figs. 5 and 6. It will be seen by this construction, that when the plate 49 is withdrawn 110 from its engagement with the lower end of the spring 48, it is possible to raise the wheel 40 and its attached bar 41 out of alinement with the member 43, the spring 48 and rod 46 passing through the aperture 45, thereby 115 permitting the wheel and its attached members to be positioned closer to the planes of the supporting members 8 and the lower member of the plane 13.

The plate 49 has its opposite transverse edges 50 downturned to engage the transverse sides of the bar 41, thereby affording means by which the plate 49 may be guided longitudinally along said bar. The engagement of the plate 49 with the spring 48 is controlled by a locking mechanism, comprising a lever 51 fulcrumed at its lower end to a bracket on the top of the member 43 by means of a pivot pin 52, the outer end of 120

which lever 51 has attached thereto one end of a flexible member 53, said latter member passing through an aperture directly below in the member 43, about pulleys 54 and 55 carried by the member 43, about a drum 56 convenient to the operator, and about pulleys 57 to one end of a reach rod 58 on top of the lowest end of the member 43. The reach rod 58 is of a general U-shape construction, as shown more particularly in Fig. 6, the opposite free ends of which are outturned to engage in an aperture 59 in a pair of spaced-apart brackets 60 extending upwardly from the top of the plate 49. To force the plate into engagement, to support the spring, there is also attached to the lever 51, intermediate its length, an auxiliary stop-actuating rod 61, of a general U-shape construction, the opposite ends of which are outturned to engage in a pair of the apertures 59 in the brackets 60 on the plate. It will be seen that rotating the drum 56 in one direction, by means of a crank 62, the plate 49 is withdrawn from its engagement with the spring 48, by drawing the rod 58 in the direction of the arrow, thereby permitting the wheel 40 and its attachments to be raised by any suitable means, which raised position is indicated in dash lines in Fig. 5, or by rotating the drum in the opposite direction, the lever 51 is lowered forcing the plate to engage the spring. It is to be understood that the one drum 56 may be used to unlock simultaneously both of the rods carrying the wheels 40, and to raise them close to the body of the device, as shown in dash lines in Fig. 5. In order to fasten the plate 49 in a retracted position out of engagement with the spring, there is extended from the top face of the plate, a suitable spring catch 63 adapted to engage a transversely-disposed catch rod 64 carried by the bar 41. It is, of course, to be understood that rotating the drum 56 in the opposite direction, will draw the lever 51 downward, thereby forcing the plate 49 forward toward the wheel, or until the centrally-disposed recess 65 in the plate 49 contacts with the rod 46 and the plate adjacent this recess 65 affords a bearing or stop for the spring 48.

Having thus described my invention, I claim as new and desire to secure by Letters Patent:

1. In a flying machine, a plane having swinging ends, a steering post, the lower end of which is mounted in a ball and socket joint, a pair of half circular wheels carried by the post, a pair of pulleys disposed on opposite sides of the steering post, a vertically disposed wheel operatively connected with each swinging end of the plane, and a flexible connection secured to each vertically disposed wheel, passed around the pulleys at the sides of the steering post and looped

in opposite directions about the half circular wheels on the steering post.

2. In a flying machine, a plane having swinging ends, a pivoted steering post, wheels on the post, a pair of pulleys disposed on opposite sides of the steering post adjacent thereto and, between which the steering post is adapted to swing, a flexible connection passed around the pulleys and looped in opposite directions about the wheels on the steering post, and means connected with the swinging ends of the plane and operated by the said flexible connection. 70 75

3. In a steering mechanism, a steering post, a support, a ball-and-socket connection between said post and said support, a pair of arms rigidly attached to said post, said arms curving downward from said post, so as to bring the outer ends thereof in a line passing through the center of said connection, flexible connections attached to the ends of said arms, a pair of semi-circular wheels disposed in opposite directions on said post, a pair of shafts disposed on opposite sides of said post and rigidly mounted on said support, a pair of pulleys carried by each of said shafts, and a flexible connection attached to each of said wheels, each passing about one of said pairs of pulleys. 80 85

4. In a flying machine, a pair of rear planes arranged one above the other, pairs of braces extending rearwardly beyond the planes, a vertically disposed rudder mounted between each pair of braces, a strut connecting the rudders, a steering post, and flexible connections between the post and strut of the rudders. 90 95 100

5. In a flying machine, a plane having swinging ends, a steering post mounted to turn and swing and provided with oppositely projecting arms and wheels, pulleys on opposite sides of the steering post, a flexible connection passed around the pulleys and looped in opposite directions about the wheels on the steering post, means connected with the swinging ends of the plane and operated by the flexible connection, pivoted rudders, and a flexible connection connecting the arms of the steering post with the rudders. 105 110 115

6. In a flying machine, a plane at the forward end of the machine and having flexible ends, a pair of rudders at the rear end of the machine, a steering rod mounted to turn, oppositely projecting arms adjacent the lower end of the rod, cables secured to the arms and connected with the rudders, semicircular wheels on the steering rod above the said arms, and cables secured to the said wheels and the flexible ends of the plane. 120 125

7. In a flying machine, forward planes arranged one above the other, and each having its rear edge centrally recessed, rear planes trapezoidal in form and arranged one above the other, each of the said rear planes 130

having its forward edge recessed, and a propeller mounted in the opening formed by the recesses of the said planes.

8. In a flying machine, forward planes
5 arranged one above the other, the upper plane being smaller than the lower plane and each having its rear edge centrally recessed, rear planes trapezoidal in form and arranged one above the other, each of the
10 said rear planes having its forward edge recessed, and a propeller mounted in the opening formed by the recesses of the planes approximately about midway between the planes.
- 15 9. In a flying machine, forward planes arranged one above the other and each having its rear edge recessed, the upper plane

being of less width than the lower plane and having its side edges converging toward the rear and meeting the curved outlines of the 20 recess, rear planes trapezoidal in form and arranged one above the other the planes being smaller than the forward planes and each having its forward edge recessed, and a propeller mounted in the opening formed by 25 the recesses of the planes.

In testimony whereof I have signed my name to this specification in the presence of two subscribing witnesses.

ERNST W. F. HERRMANN.
